HOT MILL CATCHER

George Hartill, Sr., Gary, Ind.

Application November 12, 1931
Serial No. 574,614

2 Claims. (Cl. 80—43)

This invention relates to hot mill catchers and more particularly to hot mill catchers for tin mills and the like, such as shown and described in United States Patent No. 1,767,574, issued to Dario Buccicone on June 24, 1930.

The object of this invention is to provide a stop or holding device for retaining the hot sheets or packs at the top of the mill until the operator has had time to break down the corners of the pack or is ready to grip the packs or sheets in readiness for another pass through the mill.

In the drawings:

Figure 1 is a plan of a catcher constructed in accordance with this invention.

Figure 2 is a side elevation thereof.

Figure 3 is a sectional elevation taken on the line III—III of Figure 1.

Figure 4 is an enlarged fragmentary sectional elevation of the delivery end of the catcher.

Figure 5 is a sectional elevation taken on the line V—V of Figure 4.

Referring more particularly to the drawings, the letters A and B designate the upper and lower rolls of a hot mill.

The catcher of this invention comprises a wheeled frame C having upper side members 2 and extension side plates 3 and 3^a at its forward end. The extension side plates 3 and 3^a are spaced vertically so as to provide clearance along the path of travel of the sheets or packs, and thereby permit the catcher to handle maximum width sheets or packs from the mill.

A pair of pinch-rollers 4 and 5 are journaled in suitable bearings 6 and 7 in the side plates 3 and 3^a respectively, and are adapted to receive the plates as they pass from between the mill rolls A and B. A second set of pinch-rollers 8 and 9 is journaled in bearings 10 and 12, respectively, in side plates 3^b which connect the side plates 3 and 3^a. The upper bearings 6 and 10 for the upper roller of said pairs of pinch-rollers are spring pressed so as to permit the plates to pass therebetween. The upper roller 8 of said second pair of pinch-rollers is limited in its movement toward the roll by a block 8^a so as to maintain said rollers in spaced relation.

A compound wound motor 14 is mounted on the frame C and is provided with a pinion 15 which meshes with a gear 16 on a drive shaft 17. A sprocket 18 is mounted on the shaft 17 and is connected with a sprocket 19 on the lower pinch-roller 5 by a chain 20 so as to normally drive the roller 5 in a clockwise direction. The upper pinch-roller 4 is in frictional engagement with the roller 5 so that the roller 4 will be driven in

a counter-clockwise direction. The roller 4 is provided with a drive sprocket 21 which is connected to a sprocket 22 on a rear roller 23 by a chain 24. The roller 23 is of the disk type and is journaled in fixed bearings in side plates 3 and 6^a and is adapted to aid in conveying the sheets or packs over the rolls when they are returned by the catcher.

The roller 23 is provided with a second sprocket 25 which is connected by a chain 26 with a sprocket 27 on the upper pinch-roller 8.

From the above it will be readily seen that the single motor 14 serves to drive the pair of pinch-rollers 4 and 5, the conveying or plate return roller 23 and the upper roller 8 of the 70 pair of pinch-rollers 8 and 9.

Guide plates 29 are mounted between the pairs of pinch-rollers and serve to support the hot sheets or packs as they pass from one pair of pinch-rollers to the other. Other guide plates 75 30 are mounted on a cross member 30^a of the frame C and serve to support the hot sheets or plates as they pass from the pinch-rollers 8 and 9.

A single conveying roller composed of a shaft 80 31 having disks 32 secured thereon is journaled in bearings 33 adjacent the forward ends of side members of the frame C. A jackshaft 34 is journaled on the frame C below the single conveying roller and has a sprocket 35 and gear 85 36 secured thereon. The sprocket 35 is connected by a drive chain 37 to a sprocket 38 on the drive shaft 17 and the gear 36 is meshed with a gear 39 on the shaft 31 of the conveying roller, whereby said roller is operated by 90 the motor 14 which drives the pinch-rollers 4 and 5, and 8 and 9.

A conveying table E composed of side members 40 and transverse members 41 is provided with a trunnion shaft 42 intermediate its ends 95 which is journaled in bearings 43 secured to the frame side members 2. A plurality of conveyer rolls Y are arranged in spaced relation along the side members 40 of the table E and are composed of shafts 44 journaled in bearings 100 45 of the table side members 40, which shafts have disks 46 secured thereon.

A reversing motor 47 is mounted on the frame C and has its armature shaft provided with a pinion 48 which is meshed with a gear 49 on 105 a jackshaft 50 journaled on the frame C. The shaft 50 is in vertical alignment with the trunnion shaft 42 of the table E.

A pair of jackshafts 51 and 52 extend transversely of and are journaled in the side mem- 110

bers 40 of the table E. The shafts 51 and 52 are respectively spaced an equal distance from the opposite sides of the trunnion 42.

5 The shafts 50, 51 and 52 are provided with sprockets 53, 54 and 55, respectively, which are connected by a drive chain 56. The shafts 51 and 52 are provided with other sprockets 57 and 58, respectively, which are connected with sprockets 59 and 60 secured to the roller shafts 10 44 adjacent the shafts 51 and 52 by chains 61 and 62.

15 All of the conveyer roller shafts are provided with sprockets 63 which are connected by chains 64 so that all of the rollers Y will rotate in unison in the same direction.

20 The motor 47 is adapted to normally rotate in a direction to rotate the shafts 50, 51 and 52 and the rollers Y in a counterclockwise or forward direction toward the mill. Therefore, 25 the chain 56 will be tensioned between the sprockets 53 and 54 and will pull down the forward end of the table E. When a sheet or pack has reached its full length it will cause the motor 47 to be reversed by automatic control mechanism including the switch 69. This mechanism forms no part of this invention, and will not be further discussed.

30 When the motor 47 is reversed the tension of the chain 56 will be transferred to the point between the sprockets 53 and 55. This transfer of the tension point of the chain 56 will rock the table E in reverse direction so as to position it substantially on a horizontal plane, thus facilitating the discharge of the first length of 35 sheets or packs from the table.

40 With the table in its normal position, that is,—inclined forwardly or toward the mill, the sheets or packs, when they are delivered from the bite of the pinch-rollers 8 and 9 onto the conveyer rollers Y of the table E, will be reversed or fed forwardly by the conveyer rollers Y over the rollers 8, 23 and 4 onto the top roll A of the mill and, due to the constant operation of these rollers and mill roll in a counterclockwise direction, the plates will be conveyed over the mill unless stopped or retained by the means to be now described.

45 In order to prevent the automatic delivery of the sheets or packs over the mill I provide a retaining mechanism consisting of a pair of retarding bars 70 which are provided with a pair of lugs 71 adapted to straddle brackets 73 mounted on the top guide plate 29 of the catcher and pivoted or swiveled on pins 72 secured in the 50 brackets 73. The lugs 71 are mounted at a point slightly forward from their horizontal center so that the portion of the bars 70 to the rear of the lugs 71 will normally overbalance the portion of the bars forward of the lugs 71 and thereby tilt the forward portions of the bars 55 upwardly. The bars 70 lie between the disks of the roller 23 and have their rear ends curved so as to normally lie below the roller 8 and

have their forward ends curved upwardly and forwardly to form a substantial cam-like surface 75 normally extending into the line of travel of the sheets or packs being moved forwardly by the rollers 8, 23 and 4 in their return over the mill.

80 As the sheets or packs move forwardly over the rollers 8, 23 and 4 their forward edges will engage the curved surface 75 of the bars 70 so as to force said bars to tilt or rock about the pins 72 so as to cause the rear ends of said bars to move upwardly while their forward curved ends move downwardly, thus raising the sheets or packs from engagement with the rollers 8, 23 and 4 and retarding or stopping the forward movement 85 of the sheets or packs in such a position that their forward ends will be suspended over the top roll A of the mill. The sheets or packs will be retained in this position until the roller or operator has had sufficient time to break down the pack and to grip the sheets or packs so as to pull them over the mill for another pass through the mill.

90 In order to retain the bars 70 in their normal position stop lugs 76 are provided to the rear of the lugs 71 and are adapted to engage the brackets 73, thereby limiting the downward rocking movement of the rear portions of the bars 95 70.

95 While I have shown and described one specific embodiment of my invention it will be understood 100 that I do not wish to be limited thereto, since various modifications may be made without departing from the scope of the invention, as defined in the appended claims.

105 I claim:

110 1. In a hot mill catcher, means for conveying the sheets or packs back over the mill, a pair of retarding bars pivotally mounted on said catcher at a point adjacent the mill, said bars being positioned below the line of travel of the sheets being conveyed back over the mill for the major portion of their length, and the forward or mill ends of said bars being projected upwardly into the path of travel of the sheets, said bars being adapted to be engaged by said sheets and rocked 115 about their pivotal mounting so as to lift said sheets from said conveying means as said sheets approach the delivery point over the mill.

120 2. In a hot mill catcher, means for conveying the sheets or packs back over the mill, at least one retarding bar pivotally mounted on said catcher, said bar being positioned for a major portion of its length below the line of travel of the sheets being returned over the mill and having its forward or mill end curved upwardly into the 125 path of travel of the sheets, the sheets being returned over the mill being adapted to engage the curved forward end of said bar and to rock said bar about its pivotal mounting so as to lift said sheets out of engagement with said conveying 130 means as said sheets approach the delivery point over the mill.

135 GEORGE HARTILL, SR.
